UNITED STATES PATENT OFFICE

WILLIAM W. PRICE AND CHARLES W. RIPSCH, OF DAYTON, OHIO, ASSIGNEES TO THE BUCKEYE PORTABLE TOOL COMPANY, OF DAYTON, OHIO, A CORPORATION OF OHIO

PNEUMATIC TOOL

Application filed October 19, 1933. Serial No. 313,603.

This invention relates to improvements in air driven tools or implements designed to rotate at high speeds, for the purpose of operating emery wheels, drills and other similar tools.

This invention particularly relates to an improved structure for the control of the admission of air to the air chambers. The valve for the admission of air is constructed in such a way as to gradually admit air so there is no sudden and abrupt starting of the device.

It is also a purpose of this invention to construct a device of this kind in which the air passage is made smooth and free from obstructing matter that might catch foreign particles in the air and finally clog up the air passage. This is done by providing a metal tube as part of the air passage, and casting the handle part around the tube in the process of manufacture.

It is a further object of this invention to provide a loose connection between the operating device and the operated part so that by removing pressure from the handle the tool may be operatively separated and having a connection which provides means whereby the tool may be changed from a loosely connected one to one in which the operating and operated parts are operatively attached at all times. For the purpose of illustration there is shown one, and the preferred embodiment of this invention, in the accompanying drawings.

In the accompanying drawings:

Figure 1 is a face view of the device showing the tool as a whole.

Figure 2 is a longitudinal section on the line 2-2 of Figure 1, showing the preferred form of device and showing the loose connection between the driving and the driven parts of the tool.

Figure 3 is a section view similar to Figure 2, but showing the permanent connection between the driving and the driven parts.

Figure 4 is a cross section through the cylinder and a five-blade rotor at or near the beginning of the air pressure on the piston.

Figure 5 is a similar view, but with a three-blade rotor in a more advanced position than that shown in Figure 4.

Figure 6 is an end view of the device shown in Figure 1, looking in the direction of the chuck member.

Figure 7 is a longitudinal section showing a form of the device having a modified air inlet and a modified tool connection from that shown in Figure 1.

Figure 8 is a top plan view of the device as shown in Figure 7, looking in the direction of the air inlet passage.

Figure 9 is a view showing the inner end of the chuck and its surrounding sleeve.

Figure 10 is an edge view of the gear that operates the tool.

Figure 11 is a side view of the same gear, showing the clutch mechanism.

Figure 12 is a modified form of air inlet passage with its air-control means.

This implement is constructed in two separate and distinct sections, one a driving section and the other a driven section. The driving member is composed of a handle constructed to control the admission of air into a cylinder, a cylinder, a rotor in the cylinder, and means for properly securing the rotor in the cylinder in a rotating condition. The rotor is also provided with a shaft adapted to connect with the driven element. The connection means on the shaft shown in Figure 2 is a gear, indicated by the numeral 52.

The driven element is composed of a casting having therein a shaft, a connecting means between the driven shaft and the shaft of the rotor. This connection may be as shown in Figure 2, or it may be a direct connection between the rotor shaft and the shaft of the driven member as shown in Figure 7.

In an implement of this kind, constructed in sections, the parts of one are interchangeable with those of another, the driven section being attached to the driving section by means of screws, or any other suitable means may be detached and replaced by another form. By constructing the tool in this manner the driven section adapted to the work to be performed may be selected and attached to the driving section.

By referring to the drawings, especially to Figures 1 and 2, it will be seen that the

tool consists essentially of three features or parts, the handle section, indicated by the numeral 1, the driving section 2, and the driven section 3. Extending from one side of the driven section is an auxiliary handle 3'. This handle is adapted to be gripped by the left hand of the operator while the right hand grips the handle part, indicated by the numeral 1.

- 10 As indicated by Figure 2 there is an air inlet passage 4 which extends entirely through the handle and at right angles to the main body of the tool. One end of this air passage is screw threaded, as indicated by the numeral 5, for the purpose of receiving a plug 6, which also has an air passage therethrough, indicated by the numeral 7. This air passage communicates with the main air passage in the handle.
- 15 The plug 6 is in screw threaded engagement with the handle, and after it has been fully and completely seated it is locked against turning by means of a key 8, shown in Figure 2. The outer end of the plug 6 is screw threaded and adapted to receive thereon a cap member 9, which has a screw threaded opening 10 in the end for the reception of an air tube.

20 Between the cap member 9 and the plug 6 there is a washer 11, and between the outer end of the plug 6 and the inside part of the cap 9 there is a strainer 12. The purpose of this strainer is to catch any dust or other foreign particles that might be in the air 25 and might, in any way, interfere with the proper operation of the device.

25 Fitting within the inlet passage 4 there is a sleeve or bushing member 13, which is adapted to cooperate with a plunger for the admission of air into the rotor of the device. Fitting within this sleeve there is a plunger 14, which has in one end an opening 15 for the admission of air. The other end of this plunger is closed. The open end is in the 45 direction of the air passages, heretofore described.

30 The open end of the plunger is closed by means of a screw threaded plug 16, and between this plug 16 and the shoulder 18 on the plug 6 there is a spring 17, which tends to move the plunger 14 up, as indicated in Figure 2, but this movement is limited by means of a shoulder 19, which contacts with one end of the sleeve 13 and forms there- 35 with a closure to prevent the leakage of air through the valve. It is therefore apparent that, due to the action of the spring, the plunger 14 is held in the extreme closed elevated position and remains in that position 40 until acted upon for the purpose of moving it.

35 Near the plugged end of the plunger 14 there is a series of diametrically arranged holes 20. These holes may be in any number but in the present instance they are represented as being four in number.

These holes are arranged in progressive relation with each other so that as the plunger is pressed for the admission of air, the air will first be admitted into one hole, and successively into the holes until all of the holes 40 are open for the admission of air into the opening 15, from which the air is admitted through opening 21 into the tube 23.

45 The hole 21 is situated in relation to the holes 20 in such a way that as air is admitted through the first one of the holes 20, the hole 21 is open, or this hole 21 may be so arranged that the air is not immediately admitted into it but is admitted only after the first hole 20 is slightly opened.

50 By this arrangement there is provided a valve that combines the features of both a poppet valve and a cylindrical valve, whereby a valve is provided that seals perfectly and that admits air gradually, and one that can be controlled in such a way that the admission of air is gradually effected. In many valves this control of the admission of air is not possible.

55 On the valve becoming slightly opened the pressure is released and a consequent rush of air is effected, but such is not the case in the operation of this valve. On the initial opening of the valve there is no tendency to further rapid and uncontrolled opening of the valve.

60 When this opening 21 is moved Figure 2, due to pressure on the valve, it is brought into alignment with a hole 21', which passes through the part of the handle between the inlet passage 4 and the air passage 22 formed in the handle adjacent the air passage 4. This air passage 22 is formed from a tube of metal having each end mashed so that the sides are in close contact with each other, as indicated by the numeral 22'.

65 After this tube has been thus formed, with the ends thus closed, the metal that forms the body of the handle is cast around the tube, thereby causing the tube to be permanently embedded in the metal composing the handle of the device. This tube is indicated by the reference numeral 23. The end of the tube, near the rotor, is bored out and leads into an air passage 24, leading to the rotor.

70 For the purpose of operating the plunger 14 there is provided a lever 25, which is suitably located in a slot 25' in the handle part of the device. This lever, near one end, has an elongated slot 26 through which there passes a pin 27. This pin serves as a pivot around which the lever works and on which the lever may have longitudinal movement, due to the elongated slot 26.

75 Extending from one side of the lever 25 there is an arm 28, which engages the outer or closed end of the plunger 14 for the purpose of operating the plunger to open or close the passages 20 and 21. Near the other end of the slot 25' there is a pin 29, similar to pin 120

27, which is adapted to engage a notch 30 in the other end of the lever 25, and hold the lever in engagement with the plunger 14 so that the air passages are continually open from the air hose into and through the air passage 24 to the rotor.

For the purpose of operating the lever 25 there is provided, on the outer end thereof, a thumb piece 31. This thumb piece is conveniently located for operation by the thumb of the hand which grips the handle. After the handle has been pressed it may be slipped longitudinally so that the notch 30 engages the pin 29 and remains in this position until released, and in this position the air passages are open for the operation of the rotor.

The foregoing is a description of the handle section and the means by which the air is admitted to the rotor. The driving section is inclosed in a casing more or less cylindrical in shape, indicated by the numeral 32. The body of this part of the device is formed of one piece of metal, or cast together with the handle part.

25 The inner part of the cylindrical casing 32 has a reduced part 33. In the part of the cylinder near the handle there is located a circular bearing plate 34. This bearing plate is made of some suitable material, and has a hole through the center thereof to receive the rotor shaft, hereinafter described. Extending from the circular bearing plate 34 is a circular flange 35, which is adapted to fit within the reduced part 33 of the cylinder.

35 Immediately within the cylinder 32 there is a second cylinder 36, which might be called the operating cylinder, and is composed of any suitable material, so that it will resist wear. Between the cylinder 32 and the cylinder 36 there is a circumferential cavity, which aids in the exhaust and also in deadening the exhaust sound.

On the other end of the cylinder 32, and fitting against the cylinder 36, is a second bearing plate 37. This bearing plate is held in engagement with the other part of the adjacent structure by means of a screw threaded ring 38. The second bearing plate 37 is somewhat similar in structure to the bearing plate 34, and has an opening therethrough for the reception and operation of the rotor shaft.

45 The two bearing plates 34 and 37, together with the cylinder 36, form the cavity in which the rotor and the rotor shaft operate. The bearing plate 37 also has a circular flange, similar to that on the bearing plate 34, and indicated by the numeral 39. These flanges on the bearing plates are circular and on the center of the bearing plates.

60 Extending through the openings in the bearing plates is a shaft 40, to which the rotor 42 is splined, as indicated by the numeral 41. The rotor is circular in shape and is adapted to rotate within the circular cylinder and in contact with one side. The rotor,

being smaller in diameter than the inside of the cylinder 36, there is considerable space between the rotor and the side of the cylinder out of contact with the rotor. The space between the rotor and the cylinder is the compression space and adapted to receive air, under compression, for rotating the rotor.

The openings in the bearing plates 34 and 37, through which the shaft 40 passes and in which it rotates, are indicated by the numeral 43. These openings are on the center of the plates and are in the center of rotation of the rotor.

The rotor 42 has on the circumference thereof a series of serrations, indicated by the numeral 42'. These serrations are merely hollowed out cavities on the surface of the rotor and may or may not extend the full length of the rotor.

The purpose of these serrations, constructed as indicated in Figures 4 and 5, is to form surfaces against which the air impacts as it enters into the cylinder to aid in the rotation of the rotor. These serrations need not be very deep, and are somewhat exaggerated in Figures 4 and 5.

On each end, or near each end of the rotor shaft there is a bearing ring 44. On the inside of each of the flanges 35 and 39 there is a bearing plate 45. These bearing plates cooperate with each other to form a runway in which there is anti-friction means 46 in the shape of ball bearings. This structure is fully shown in Figures 2 and 3.

Leading from the air passage 24 is an air passage 47, which leads into the cylinder 36. It is through this passage 47 that the compressed air passes to operate the rotor. In the rotor there is a series of radially arranged slots 48. There may be any number of these slots. In Figure 5 three are shown, while in Figure 4, five are shown. In each of these slots there is located a blade 49, which is adapted to slide in and out in the slots 48 in contact with the inside surface of the cylinder 36. These blades are kept in contact with the surface of the cylinder by centrifugal force, due to the rapid rotation of the rotor 42.

After the air, which is admitted through 47, has completed its work by expanding and forcing the rotor to rotate, its passes out through the exhaust 50, as indicated in Figures 4 and 5. These exhausts lead from the inside of the cylinder 36 into the space between the inner and outer cylinders.

There is shown extending through the longitudinal center of the shaft 40 the hole indicated by the numeral 51, for the purpose of conducting a lubricant from one end of the shaft to the other. It is necessary in tools of this kind that they be well lubricated. By means of this hole the lubricant can be conveyed from the driven end of the implement,

through and around the parts of the driving element.

On one end of the shaft 40 there is a gear, indicated by the numeral 52, which is adapted to mesh with and engage the parts of the driven element. Instead of having a gear on the end of the shaft 40 any other suitable means for connecting the driving element with the driven element might be used, depending upon whether the connection is to be direct or mediate.

The driven part of the device is inclosed in a casing 53, which is attached to the driving part of the device by means of screws 54.

15 The casing 53 has an opening on one side for the purpose of inserting the gearing that operates within the casing. This opening is closed by a plate or closure 53', as clearly shown in Figures 1 and 2. To one side of the 20 casing inclosing the driven mechanism there is a small chamber 55, which houses intermediate gears 57 and 58 and shaft 56. This shaft has on one end thereof gear 57, which meshes with the gear 52 on the end of the 25 rotor shaft 40.

There is also, in the center of this shaft 56, the second gear 58, which meshes with the gear 60. The shaft 56 is suitably mounted in bearings 59. These bearings are similar 30 to those in connection with the rotor shaft 40. The gear 60 is mounted upon a shaft 61.

One end of this shaft is supported in suitable bearings 62, similarly constructed to the other bearings hereinbefore described. The 35 other end of this shaft 61 is larger and is adapted to receive over it a chuck member 65. The outer end of the casing 53 that houses the driven mechanism is formed in a cylindrical cavity 63, which has therein a cylindrical sleeve 64. This cylindrical sleeve 40 is permanently mounted in the casing and receives the barrel part of the chuck 65.

On the inside hollow end of the barrel chuck there is a clutch member 66, which is 45 adapted to engage and cooperate with a similar clutch member 67 on the gear 60. The opening in the barrel chuck is indicated by the numeral 68 and receives the enlarged end of the shaft 61. Within this opening is a 50 spring 69 which engages the end of the enlarged part of 61, tending to hold the chuck member away and out of clutching engagement with the gear 60. The chuck 65 is adapted to both rotate and have longitudinal 55 motion on the shaft 61.

The outer end of the casing 53 is screw threaded and is adapted to receive thereon a screw threaded cap 71. There is adapted to fit within the screw threaded cap 71 and resting upon the outer end of the casing 53 a ring member 70. When this ring member 60 is inserted within the cap 71 the space between the cap and the gear 60 is increased. There is also formed on the chuck member 65 a shoulder 72. This shoulder rests against

the end part of the cap 71 and is adapted to be moved in the space between the end of the cap and the sleeve 64. In other words, between the outer end of the sleeve 64 and the outer end of the cap 71 there is provided a 70 space in which the shoulder 72 may move, due to the movement of the chuck member.

In the position as shown in Figure 2 the clutches are out of engagement with each other, and any operation of the rotor would 75 not operate the clutch, but by pressing upon the handle the chuck member 65 is forced inwardly so that the clutches engage and the chuck member rotates with the gear 60.

The advantage of this feature of the structure is that by removing the pressure from the handle the clutch mechanism can be thrown out of gear and the tool ceases to rotate, yet the rotor still continues to rotate. But by removing the ring 70, as indicated in 80 Figure 3, and placing the cap 71 so that the outer part of the cap engages the outer end of the casing 53 the space for the shoulder 72 is limited so that there is practically no play. In this structure the clutches are held 85 in permanent relation to each other, and the clutches are operated at all times that the rotor is operating. This is an interchangeable feature that makes this tool adaptable for different purposes, merely by the removal 90 of the ring 70.

The numeral 73 is used to designate a space formed by the cap member 71 and the sleeve 64 for permitting a limited degree of longitudinal movement of the chuck member 65. 100 This space 73 may be made smaller by removing the ring 70, as shown in Figure 2. When this ring 70 is removed the chuck member has no longitudinal motion whatever, and the clutches 66 and 67 are maintained in 105 permanent engagement with each other.

The outer end of the chuck member 65 is provided with a tool-receiving hole 74. Leading into this hole 74 from the outside, and through the side of the chuck member 110 are openings 75, which are adapted to receive ball members 76. Fitting on the outside of the outer end of the chuck member is a cuff member 77. This cuff member is adapted to have a limited amount of longitudinal motion on the chuck member, and is provided with a shoulder 78, which normally rests over the opening 75 and holds the balls in said openings and causes them to project partly within the opening 74, where they perform 115 the function of aiding in holding the tool in the chuck.

The outer end of the chuck member is somewhat reduced in size, and has thereon a shoulder 79. Between the shoulder 78 and the shoulder 79 there is a coil spring 80. This coil spring serves to hold the cuff member in a position so that the shoulder 78 is over the holes 75, but it also permits of the movement 120 of the cuff member so that the balls may 125

become free from the shoulder 78 and drop back into a groove 81 in the cuff member. The purpose of this movement is to allow the tool to be entered into the opening at the end 5 of the chuck. For this purpose the balls must be permitted to drop back out of line with the tool as it enters the chuck. For the purpose of limiting the outward movement of the cuff member there is provided a lock 10 ring 82, near the outer end of the chuck.

When it is desired to operate a tool by a device as shown in Figure 2, the proper end of the tool is inserted into the end of the chuck member, after the cuff has been pushed in- 15 ward so the balls may be displaced, and after the tool has been properly inserted in the chuck the cuff is permitted to move toward the end of the chuck and the balls drop into a groove in the tool and hold the tool in the 20 chuck so that it cannot be easily displaced.

The device as shown in Figure 2 is used for driving nuts and screws, drilling, grinding, burring, etc. It is frequently necessary, in work of this kind, that the power be disconnected 25 from the tool, and that is accomplished in the present device by simply moving the hand and removing the pressure from the tool so that through the spring 69 the clutches 66 and 67 are released from each 30 other. As soon as this takes place the tool itself ceases to operate while the rotor is still operating. By a structure of this kind there might be effected a slight hammer action. A twenty-degree clutch gives a hammer action 35 for screws, while a five-degree clutch is suitable for nuts and the like.

In the event that the device is to be used for emery wheels, buffers and the like the structure shown in Figure 3 is more acceptable. For this purpose there is especially 40 shown the form in Figure 7. In Figure 7 the work shaft is shown to be long and connected directly to the rotor shaft. The work shaft in this figure is indicated by the numeral 83, which is connected to the rotor shaft by 45 means of the tongue and groove structure 84. On the outer end of the shaft 83 there is shown, in dotted lines, a buffer 85, or other tool of a similar nature.

In the structure shown in Figure 7 the rotation of the rotor is transmitted directly to the tool-engaging shaft, and there is no increase or decrease in the speed of rotation of the tool shaft over that of the rotor shaft. This is unnecessary in cases where buffers or 50 polishers are used. In this instance the desire is to have speed and a high degree of revolution rather than great power. There is also shown in Figure 7 the ordinary, conventional way of admitting air to the rotor.

In Figure 13 there is shown a modified form of air control which is adapted to be inserted in the place of air control shown in 55 Figure 7. The air control shown in Figure

7 is the ordinary type and might be replaced by any suitable means.

In Figure 13 there is shown a form of poppet valve which is very efficient in accomplishing the purposes desired. This valve 70 may be opened by pressing upon the head 86 with the thumb, and when the thumb is removed the valve immediately closes though there is no spring means for holding it in closed position. This is done because of the 75 fact that the air pressure tending to close the valve is always greater than the pressure tending to open it, so that when the pressure on the head 86 is removed the valve immediately closes.

By means of these openings, by which lubricant can be supplied, the tool is kept in condition for operation at a high rate of speed. The part 87 permits of the lubricant being inserted in one end of the tool, while the part 85 88 permits the lubricant to be inserted in the other end of the tool.

There is also provided in the rotor chambers 51', in which lubricant is stored.

It is apparent from the foregoing description 90 that a device is provided in which the parts are few and relatively simple, and one in which the parts are provided with easy and efficient means for lubrication.

We desire to comprehend within our invention 95 such modifications as may be clearly embraced within our claims and the scope of our invention.

Having thus fully described our invention, what we claim is new and desire to secure 100 Letters Patent, is:

1. In a pneumatic tool, a cylinder, a valve controlled means for admitting air to said cylinder, a longitudinally movable lever for operating said valve, and means effective by 105 the longitudinal movement of the lever for locking said lever in valve operating position including a lip on said lever and a coacting means to engage the lip.

2. In a pneumatic tool, a cylinder, a valve 110 controlled means for admitting air to said cylinder, longitudinally movable means for operating said valve, and means effective by the longitudinal movement of the lever for locking said movable means in valve operating 115 position, including a lip on the movable means and a pin.

In testimony whereof we affix our signatures.

WILLIAM W. PRICE. 120
CHARLES W. RIPSCH.
